(57) CLAIM

The ornamental design for a nonwoven fabric, as shown and described.

DESCRIPTION

FIG. 1 is a front perspective view of a nonwoven fabric, embodying the new design;

FIG. 2 is plan front view of the nonwoven fabric of FIG. 1; FIG. 3 is a plan rear view of the nonwoven fabric of FIG. 1; and,

FIG. 4 is a cross-sectional view of the nonwoven fabric of FIG. 1 taken along line 4-4 of FIG. 2.

The broken lines in the figures depict portions of the nonwoven fabric that form no part of the claimed design.
